poration of New YorkApplication April 23, 1934, Serial No. 722,010
In the Netherlands April 29, 1933

6 Claims. (Cl. 176—124)

The present invention relates to gaseous electric discharge lamp devices.

A gaseous electric discharge lamp device having a gaseous filling consisting of a rare gas and a metal vapor emits light the spectrum of which contains rays characteristic of the gas and of the vapor provided the vapor is at a proper pressure. The light emitted by a gaseous electric discharge lamp the gaseous atmosphere of which 10 comprises neon and mercury vapor, for example, approximates white light. The vapor pressures of such a lamp must be controlled within narrow limits in order to obtain a balance between the light emitted by the vapor and that emitted by 15 the gas. Control of the metal vapor pressure is obtained by controlling the temperature of the vaporizable material. The vaporizable material is placed in an off set chamber communicating with the container of the lamp device and a 20 heating element is mounted in operative relation to said off-set chamber to heat the vaporizable material to a desired temperature.

This structure, while effective for a lamp the gaseous atmosphere of which comprises one 25 metal vapor, is not practical when the gaseous atmosphere comprises two or more metal vapors which are excited to luminescence during the operation of the lamp. In this case it is necessary to heat the vaporizable metals to different 30 temperatures in order to obtain an effective pressure of each metal vapor. This is not practical since the pressure of the metal vapor is controlled by the lowest temperature of the container and heating one vaporizable metal to a 35 higher temperature than another metal would be futile since the vapor pressure of all the metals in the container is determined by the lowest temperature of the container.

The object of the present invention is to provide 40 a method of and a means for operating a gaseous electric discharge lamp the gaseous atmosphere of which comprises two or more different vaporizable metals whereby both metals are luminescent during the operation of the device.

Another object of the invention is to provide a 45 gaseous electric discharge lamp emitting light comprising rays characteristic of two or more metal vapors. Still further objects and advantages attaching to the device and to its use and 50 operation will be apparent to those skilled in the art from the following particular description.

In accordance with this object the invention 55 comprises an electric discharge tube which contains the vapor of at least two metals and which

is energized by an alternating-current source of normal network frequency, (for instance 40 to 60 cycles), while the discharge current, which changes according to the frequency of the current source, is regulated in such manner that in 5 the case of a smaller current (in the rising and dropping branches of the current curve), the light of one of the metal vapors predominates, while in the case of a higher current value (at points located higher in the current curve), the 10 light of the other metal vapor predominates. In that manner, a light of a different color is obtained alternately. The frequency of this change in color is at least twice the frequency of the alternating-current source. It is practically im- 15 possible to see the color change of the emitted light when normal network frequencies are used, so that the light has a mixed color (it is of course possible to determine the color change by means of a stroboscope).

In general it is recommended to use in the 20 discharge tube a mixture of metal vapors, of which one has both a lower ignition voltage and also a lower vapor pressure than the other metal vapor.

In order to obtain a mixed light which contains 25 yellow, blue, and green rays, a discharge tube is used which contains sodium vapor and mercury vapor, for example. The current is then adjusted to such a value that at a lower current the 30 sodium light predominates, while at a higher current the mercury light predominates. The sodium light has a yellow color and the mercury light a green-blue color, so that the combined 35 light will contain both yellow lines and also green and blue lines.

In practice, a starting gas is present in the 40 discharge tubes, since the ignition is thereby facilitated. In many cases the discharge current can be given such a magnitude that during a part of every cycle the light of this gas appears. For instance, if in a discharge tube both neon and also 45 sodium vapor and mercury vapor are present, then the discharge current is regulated in such manner that the value thereof during each cycle is such that the neon light appears temporarily. In some cases it is advisable to make the mercury vapor unsaturated. The neon light adds red rays to the yellow-blue-green light.

The invention will be readily understood by an 50 inspection of the drawing accompanying and forming part of this specification and a perusal of the following detailed description thereof. In the drawing,

Fig. 1 is a front elevational, partly sectional 55

view of one embodiment of the invention, and a circuit therefor,

Fig. 2 represents the current flow through the device illustrated in Fig. 1, and

5 Fig. 3 represents an increased current flow through the device illustrated in Fig. 1.

Referring to Fig. 1 of the drawing the new and novel lamp unit comprises a U-shaped discharge tube 1 having sealed in each end thereof a ther-

10 mionic electrode 2 and a cylindrical anode 3 which surrounds the thermionic electrode 2. Said electrodes 2 comprise a coiled tungsten filament, a nickel filament wrapped around said tungsten filament and a coating of electron emitting material, such as barium oxide. The tube has a gaseous filling therein comprising neon at a pressure of a few millimeters and a quantity of sodium and mercury. The discharge tube is surrounded by a double-walled cover 4 which has 15 heat-insulating properties, while the space between the two walls of this cover has been evacuated. The two glow electrodes 2 are energized by the transformer 5. The primary windings of these transformers are connected to the alternating-current network 6 of normal frequency, for instance, 50 cycles. The current-supply wires of the anodes 3 are connected to one of the current-supply wires of the glow electrodes 2. These are connected to the network 6, while a choke coil 20 7 is connected in series with the discharge tube as a stabilization impedance.

During the operation of the discharge tube, the current which flows through the tube will have approximately the shape shown in Figure 2. 25 The current is adjusted in such a way that during the time intervals located between t_1 and t_2 , and between t_3 and t_4 , the sodium light predominates, while during the time intervals between t_2 and t_3 , the mercury light is in excess which 30 can be determined very readily by means of a stroboscope. The relation between the time intervals can be altered by changing the current values. Figure 2 shows that the color changes four times during each alternating current cycle. 35 These color changes cannot be detected by the naked eye, so that the light emitted by the discharge tube creates the impression of consisting of the combination of the yellow sodium light and the blue-green mercury light. If it is desired to have red rays instead of the yellow sodium light, then a discharge tube is used which 40 contains for instance potassium and mercury.

Take, for example, a discharge tube with a gaseous filling of neon, sodium and mercury, with 45 an electrode spacing of 40 cm., and an internal diameter of 21 mm., energized by an alternating current source with a frequency of 50 cycles and an effective voltage of 220 volts and having the choke coil adjusted in such a way that the effective value of the discharge current is 1.4 amperes. In this case the time interval between t_2 and t_3 , during which the mercury light predominated, last $\frac{3}{5}$ of a half A. C. cycle, that is, 0.01 second. During the time interval between t_3 and t_1 , (leaving the short dark period between t_4 and t_1 out of consideration), the sodium light predominates.

The current may be increased to such an extent 50 that the neon light appears at the highest value of the current. The curve of this current has been given by way of example in Figure 3. During the time intervals between t_1 and t_2 , or between t_3 and t_4 , the sodium light predominates, and during the time intervals between t_2 and t_5 , or between t_6 and t_3 , the mercury light is in

excess, while finally between t_5 and t_6 , the neon light is the strongest. In this manner a mixed light is obtained which contains yellow, blue, green, and red rays and which approximates white light very closely. In order to influence the relative intensity of the various colored light rays, it is preferable that the mercury vapor be kept unsaturated during the operation of the device by limiting the quantity of mercury therein. 5

One of the advantages of the invention lies in 10 the fact that it is possible by means of an electric discharge tube to produce mixed light with a very high efficiency.

It will be understood of course that in a complete lamp unit a base is provided to support the 15 heat conservator 4 and the container 1 and a heat insulating means is provided between the container 1 and the heat conservator 4 to close off the space therebetween from the outside atmosphere. These elements have been omitted 20 from the drawing for purposes of simplicity of illustration.

What we claim as new and desire to secure by Letters Patent of the United States is:—

1. The method of operating a gaseous electric 25 discharge lamp having a gaseous atmosphere comprising two metal vapors which consists in regulating the alternating current to said device to a frequency of 40 cycles per second at the minimum and to a magnitude such that one of 30 said vapors is predominantly luminescent during part of each cycle and another of said vapors is predominantly luminescent during another part of each cycle.

2. The method of operating a gaseous electric 35 discharge lamp having a gaseous atmosphere comprising two metal vapors having a different pressure at the same temperature which consists in regulating the alternating current to said device to a frequency of 40 cycles per second 40 at the minimum and to a magnitude such that one of said vapors is predominantly luminescent during part of each cycle and another of said vapors is predominantly luminescent during another part of each cycle. 45

3. The method of operating a gaseous electric 50 discharge lamp having a gaseous atmosphere comprising mercury and sodium vapor which consists in regulating the alternating current to said device to a frequency of 40 cycles per second at the minimum and to a magnitude such that one of said vapors is predominantly luminescent during part of each cycle and another of said vapors is predominantly luminescent during another part of each cycle. 55

4. The method of operating a gaseous electric 60 discharge lamp having a gaseous atmosphere comprising a rare gas, mercury and sodium vapor which consists in regulating the alternating current to said device to a frequency of 40 cycles per second at the minimum and to a magnitude such that one of said vapors is predominantly luminescent during part of each cycle and another of said vapors is predominantly luminescent during another part of each cycle and said gas is predominantly luminescent during another part of each cycle. 65

5. The method of operating a gaseous electric 70 discharge lamp having a gaseous atmosphere comprising neon, mercury and sodium vapor which consists in regulating the alternating current to said device to a frequency of 40 cycles per second at the minimum and to a magnitude such that one of said vapors is predominantly luminescent during part of each cycle and an- 75

other of said vapors is predominantly luminescent during another part of each cycle and said gas is predominantly luminescent during another part of each cycle, the mercury vapor being 5 unsaturated.

6. In combination a gaseous electric discharge lamp comprising a container, electrodes sealed therein, a gaseous atmosphere therein comprising a rare gas, an easily vaporizable material and 10 a difficulty vaporizable material, a choke coil

connected in series with said lamp, a 220 volt, 50 cycle current source for said lamp, said choke coil regulating the discharge current in said lamp to approximately 1.4 amperes, said gaseous constituents being excited to luminosity at different times in each cycle of said current source.
